(57) **CLAIM**

The ornamental design for automotive diagnostic cable head, as shown and described.

DESCRIPTION

FIG. 1 is a front upper perspective view the automotive diagnostic cable head showing our new design;

FIG. 2 is a front lower perspective view thereof;

FIG. 3 is a top plan view thereof;

FIG. 4 is a first-side elevational view thereof;

FIG. 5 is a bottom plan view thereof;

FIG. 6 is a second-side elevational view thereof, opposite the first-side;

FIG. 7 is a front elevational view thereof; and,

FIG. 8 is a rear elevational view thereof.

The broken lines in the drawings illustrate features that form no part of the claimed design.
